CONTROL DEVICE

Harry C. May, East McKeesport, Pa., assignor to
The Westinghouse Air Brake Company, Wil-
merding, Pa., a corporation of Pennsylvania

Original application April 30, 1943; Serial No.
485,114. Divided and this application Febru-
ary 24, 1944, Serial No. 523,656.

6 Claims. (Cl. 303—54)

This invention relates to fluid pressure control devices and more particularly to the self-lapping type, the present application being a division of my copending application Serial No. 485,114, filed April 30, 1943.

One object of the invention is the provision of an improved fluid pressure control valve device of the self-lapping type.

Another object of the invention is the provision of a self-lapping valve device so constructed and arranged as to require a relatively small degree of effort for adjusting or controlling it.

Other objects and advantages will be apparent from the following more detailed description of the invention.

In the accompanying drawing, the single figure is a longitudinal sectional view of the improved self-lapping control valve device.

Description

As shown in the drawing, the improved self-lapping valve device comprises a casing 12 having a bore lined with a sleeve 80 one end of which extends above the casing while the opposite end opens to a pressure chamber 81 formed above a flexible diaphragm 82. Above chamber 81 is an annular cavity 83 encircling the sleeve 80 and open through a plurality of ports 84 in the sleeve to the interior thereof. The cavity 83 is also open to an outlet passage 85 which may be connected to a pipe (not shown) in which it is desired to vary pressure of fluid for controlling a chosen operation or device. The chamber 81 is connected through a stabilizing choke 86 to the outlet passage 85.

The diaphragm 82 is arranged in coaxial relation with the sleeve 80 and is clamped around its edge between the casing 12 and the adjacent end of a casing section 87. An oppositely arranged and axially aligned flexible diaphragm 89 of substantially the same area as diaphragm 82 is clamped around its edge between the opposite end of casing section 87 and a cover 90. A chamber 91 is formed between the diaphragm 89 and cover 90 and is in constant communication with the atmosphere through a breather opening provided in an insect excluder 92. The adjacent faces of the two diaphragms 89 and 82 are open to chambers 93 and 94 respectively, which are in permanent communication with each other through a passage 95 provided in an annular rib 96 extending inwardly from the casing section 87 above the diaphragm 89. In use, chamber 94 and thereby chamber 93 are constantly sup-

plied with fluid under pressure from a fluid pressure supply pipe 35.

The central portion of diaphragm 82 is clamped between two followers 100 and 101, the follower 101 engaging a collar 102 provided on a stem 103 which extends through chamber 94 and through said followers and diaphragms into chamber 81. A nut 99 disposed in chamber 81 has screw-threaded engagement with the wall of a bore 104 provided in the end of stem 103 and is tightened against the follower 100 for clamping the two followers to the opposite faces of the diaphragm 82 and for thereby securing the one end of stem 103 to said diaphragm.

The rib 96 has a bore lined with a wear bushing 105 arranged in axial alignment with the two diaphragms, and the stem 103 extends through this bushing and centrally through the diaphragm 89 into chamber 91. Above the rib 96 the stem 103 is reduced in section to provide a shoulder 106, and a wear sleeve 107 is mounted on this reduced portion of the stem with one end in engagement with said shoulder. The sleeve 107 extends through the bushing 105 in sliding contact therewith and its opposite end contacts a follower 108 which is disposed in chamber 93 in contact with the upper side of diaphragm 89. The stem 103 extends through the follower 108 and a follower 109 mounted against the opposite side of the diaphragm 89 and a nut 110 provided on the end of stem 103 within chamber 91 is tightened against the follower 109 clamping same centrally to one side of the diaphragm 89 and thereby securing the follower 108 against the opposite side of said diaphragm.

In chamber 94 the rib 96 supports one end of a control spring 111 the opposite end of which bears against an annular spring seat 112 which is slidably mounted on stem 103 and urged by said spring into contact with a shoulder 113 on said stem. The spring 111 is preferably fully expanded with the parts of the device in the position shown in Fig. 1 and is operative to oppose downward movement of the stem 103 and thereby of diaphragms 82 and 89 from this position, as will be later described.

The nut 99 above the diaphragm 82 has an upwardly extending sleeve-like projection 114, the end of which is mounted to slide in the lower and adjacent end of sleeve 80 below the ports 84. The bore 104 in the diaphragm connecting stem 103 is in permanent communication through one or more bores 115 with chamber 94 and contains a fluid pressure supply valve 116. This valve has a fluted stem 117 extending through an

axial bore in the nut into the sleeve-like projection 114 thereof, wherein it contacts a preferably separately formed, fluid pressure release valve 118. The nut 99 is provided in bore 104 with a seat for engagement by the supply valve 116 and a spring 119 contained in said bore acts on said valve for urging same into contact with said seat.

A plunger 123 is slidably mounted in sleeve 80 above the release valve 118 and is provided with an annular groove 124 containing a sealing ring 125 contacting the bottom of said groove and the inner wall of said sleeve for preventing leakage of fluid under pressure from a chamber 126 below the plunger to an annular chamber 127 above the plunger. The chamber 126 is in permanent communication with the interior of the projection 114 of nut 99 and through the ports 84 with the annular cavity 83 encircling the sleeve. The chamber 127 above the plunger 123 is in constant communication with the atmosphere through one or more radial ports 129 provided in the sleeve 80.

The plunger 123 has a portion 130 of reduced section depending therefrom into chamber 126 and provided with an axial bore opening through a valve seat on its lower end which seat is provided for engagement by the release valve 118. The release valve has a fluted stem 131 extending through this seat and bore into a bore 132 of larger diameter in which there is slidably mounted a spring seat 133 having one or more openings 134 adjacent its peripheral edge connecting the spaces at the opposite sides of said seat.

The plunger 123 also has an upwardly projecting portion 135 of reduced section extending through chamber 127 and in sliding engagement with an inturned collar 136 provided at the upper end of sleeve 80. The bore 132 extends to a point above the collar 136 where it joins a screw-threaded bore 137. Just below the end of the screw-threaded bore 137 the portion 135 of the plunger has two oppositely arranged radial bores 138 in which are disposed pins 139 extending from opposite ends of a cylindrical spring seat 140 which is of slightly smaller diameter than bores 138 so that said seat may be inserted into bore 132 through either of the bores 138. A coil spring 141 is disposed in bore 132 under pressure and acts at one end on the spring seat 133 and at the opposite end on spring seat 140, this spring biasing the release valve 118 to its open position shown and moving the spring seat 140 upwardly until the pins 139 engage the uppermost portions of bores 138 in which position the spring seat 140 is held against longitudinal movement and thus secured within the bore 132. The spring 141 acts to constantly maintain the release valve 118 in engagement with the end of the supply valve stem 117.

An operating screw 145 is threaded into bore 137 in the upper end of the plunger projection 135 and on its outer end is provided with a head 146. A lock nut 147 mounted on screw 145 is arranged to engage the end of the extended portion 135 of the plunger for securing the screw 145 in an adjusted position. A coil bias spring 148 encircles the portion of sleeve 80 extending above the casing and is supported at one end on said casing and the opposite end bears against a ring-shaped seat 149 secured on the extended portion 135 of the plunger by any suitable interlocking means 150. This spring is under relatively light pressure for biasing the plunger 123 in an upwardly direction and out of seating contact with the release valve 118.

The head 146 of the actuating screw 145 and

thereby plunger 123 are adapted to be moved downwardly from a normal position in which they are shown in the drawing, by any suitable means, such as a rockable cam 154 supported on an operating shaft 155 and connected to an actuating lever 17. The cam has two reversely arranged but otherwise identical cam surfaces 160 and 161 joined together by a depression 162. Interposed between and connecting these cam surfaces and the head 146 of the adjusting screw 145 is the cylindrical end 165 of an arm 164 the opposite end of which may be supported to rock on a fixed point (not shown).

In operation when the cam 154 and lever 17 are in their normal or neutral positions, as shown in the drawing, the depression or recess 162 is positioned to receive the cylindrical end 165 of the follower arm 164 to permit spring 148 acting through seat 149 on the plunger extension 135 and thereby on plunger 123 to move said plunger and the adjusting screw 145 to their normal positions shown in the drawing. Upon rocking of lever 17 out of its neutral position in either one or the opposite direction, the cam 154 will act to displace plunger 123 into the sleeve 80, while rocking said lever back toward neutral position will permit spring 148 to move said plunger out of said sleeve. It will thus be seen that with lever 17 in its neutral position the plunger 123 will occupy its normal position shown in the drawing, while with said lever out of neutral position, the plunger 123 will be displaced from its normal position into sleeve 80 a distance proportional to that which lever 17 is out of neutral position.

When the screw head 146 and plunger 123 are in their normal positions shown in the drawing, the spring 119 will seat the supply valve 116 and spring 141 acting on stem 131 of the release valve 118 will maintain said release valve in contact with the end of the supply valve stem 117 and thus out of contact with its seat on the end of the portion 130 of plunger 123. As a result, chamber 126 below the plunger 123 and thus the connected annular cavity 83, outlet passage 85 and chamber 81 above diaphragm 82 will be open to the atmosphere past the release valve 118.

If now the cam 154 is operated to displace the screw head 146 and plunger 123 out of their normal positions against the biasing force of spring 148, the movement of said plunger will be relative to the release valve 118 until said valve is engaged by its seat provided on the portion 130 on said plunger. This seating of the release valve will close the fluid release communication to the atmosphere as will be apparent. Further movement of the plunger 123 into sleeve 80 will then act through the release valve 118 and stem 117 of the supply valve 116 to move said supply valve relative to the diaphragm 82 and thus out of contact with its seat on the end of nut 99.

When the supply valve 116 is thus opened, fluid under pressure will flow from chamber 94 past said valve to chamber 126 and thence to the outlet passage 85 and to the device (not shown) which it is desired to control. Fluid under pressure supplied to the outlet passage 85 will also flow through stabilizing choke 86 to chamber 81 above the diaphragm 82, said choke being provided to prevent the pressure in chamber 81 increasing substantially ahead of the increase in passage 85 by the supply of fluid under pressure to said passage.

The pressure of fluid thus supplied to chamber 81 past the supply valve 116 acts on diaphragm 82 in opposition to the force of control spring

111, and when this pressure is increased to a degree which overcomes said spring, it deflects the diaphragm in a downwardly direction relative to the supply valve 116 and finally into seating engagement with said valve to prevent further flow of fluid under pressure to the outlet passage 85 and diaphragm chamber 81. The increase in pressure in chamber 81 being thus limited, the deflection of diaphragm 82 will therefore cease with seating of the supply valve 116 10 and under which condition the release valve 118 will also be closed.

It will now be seen that the pressure of fluid obtained in chamber 81 and in the outlet passage 85 is limited in accordance with the extent of movement of the supply valve 116 away from its normal position shown in the drawing, or in other words, in accordance with the extent of movement of the adjusting screw 145 after closing of the release valve 118.

If it is desired to increase the pressure of fluid in the outlet passage 85, the cam 154 will be operated to displace the plunger 123 further in the direction of the diaphragm 82 which will again move the supply valve 116 relative to said diaphragm and out of contact with its seat, this relative movement being obtained since the diaphragm 82 at this time is in a static condition with respect to the pressure of spring 111 and opposing pressure of fluid in chamber 81. This unseating of the supply valve 116 will again allow fluid under pressure to flow to the outlet passage 85 and to chamber 81 above diaphragm 82. The increase in pressure in chamber 81 will then again deflect said diaphragm in a downwardly direction relative to and finally into contact with the supply valve for limiting the flow of fluid under pressure to passage 85 and thus the pressure of fluid obtained in said passage in accordance with the new position of the actuating screw 145 and of the supply valve 116 with respect to their normal positions.

It will thus be seen that the pressure of fluid in the outlet passage 85 may be increased in any desired increments by suitable increments of displacement of the adjusting screw 145 and supply valve 116 away from their normal positions shown in the drawing. A maximum pressure of fluid may be provided in the outlet passage 85 by movement of the adjusting screw 145 to a position in which the spring seat 149 in the extension 135 of the plunger is in substantial contact with the adjacent end of sleeve 80.

If after fluid under pressure is supplied to the outlet passage 85 it is desired to reduce the pressure therein, then the cam 154 and lever 17 may be turned back toward their neutral position to allow movement of the adjusting screw 145 and plunger 123 upwardly by spring 148. With the diaphragm 82 in a balanced condition by the pressure of fluid in chamber 81 and the opposing pressure of spring 111, this movement of the adjusting screw 145 and plunger 123 will be relative to the release valve 118 which will be maintained in contact with the supply valve stem 117 by spring 141. As a result, the plunger 123 will move out of seating engagement with the release valve to thereby allow release of fluid under pressure from the outlet passage 85 and chamber 81 above the diaphragm 82. The pressure of fluid in chamber 82 acting on diaphragm 81 in opposition to that of spring 111 will therefore be reduced and said spring will accordingly deflect the diaphragm 81 in the direction of the plunger 123 in accordance with the degree of such reduction,

As the diaphragm 81 is thus moved upwardly the supply and release valves 116 and 118 are moved with the diaphragm by spring 119 and such movement will be relative to the plunger 123.

5 The pressure of fluid in the outlet passage 85 and chamber 81 will thus continue to reduce until the release valve 118 moves into engagement with its seat on plunger 123, in case said plunger is still out of its normal position. This seating of the release valve 118 will then prevent further release of fluid under pressure from the outlet passage 85 and chamber 81, thus limiting the pressure in said passage and chamber to a degree determined by the distance the plunger 123 and regulating screw 145 are still away from their normal or neutral positions.

If it is desired to make a further reduction in pressure of fluid in the outlet passage 85, the lever 17 may be turned further toward its neutral position and the structure will again operate in the same manner as just described to effect a further and corresponding reduction in pressure of fluid in the outlet passage 85. It will thus be seen that the pressure of fluid in the outlet passage 85 can be reduced in any desired increments determined by the extent of movement of lever 17 back toward its neutral position. When the lever 17 is returned to neutral position and the adjusting screw 145 and plunger 123 are returned to their normal position under the action of spring 141, a complete release of fluid under pressure will occur from the outlet passage 85 and chamber 81, since at the time the pressure in said passage and chamber became reduced to substantially that of the atmosphere, the spring 111 will be fully expanded and the release valve 118 will still be unseated.

40 If it is desired to increase the pressure of fluid in passage 85 from that of the atmosphere to a maximum degree in a single step, such may be accomplished by moving the adjusting screw 145 from its normal position to its maximum pressure condition above described without intermediate stops as will be apparent. On the other hand, if it is desired to reduce the pressure of fluid in passage 85 to that of the atmosphere in a single step that may be accomplished by return of lever 17 directly to neutral position from whatever position it may be in outside of neutral position, as will also be apparent.

45 From the above description it will now be noted that the effort required to operate the improved control device to supply fluid under pressure to the outlet passage 85 is limited substantially to that required to overcome the pressure of fluid in chamber 126 acting on one side of the relatively small plunger 123, plus that required to open or unseat the supply valve 116 and is thus independent of the relatively great force of the control spring 111. It is of course apparent that with outlet passage 85 open to the atmosphere there will be no pressure of fluid in chamber 126 to oppose downward movement of the plunger 123, and it will be further apparent that the force which opposes such movement of plunger 123 will increase as the pressure of fluid is increased in said passage. However, with the maximum degree of pressure effective in passage 85 and in chamber 126 on the plunger 123 the effort required to move the plunger 123 will still be only a small portion of that required to counteract the pressure of the control spring, and this is important, particularly in case of manual control of the device as by lever 17, since it provides for very accurate adjustment of the device

in accordance with the pressure of fluid desired to be provided in the outlet passage 85 and will also minimize fatigue on the part of an operator.

Having now described the invention, what I claim as new and desire to secure by Letters Patent, is:

1. A self-lapping valve structure comprising in combination, two connected movable abutments cooperating to form a pressure chamber normally charged with fluid under pressure, a spring in said pressure chamber acting on one of said abutments, a supply valve movable relative to said one abutment to open communication between said pressure chamber and a receiving chamber at the opposite side of said one abutment, said abutments being movable by pressure of fluid supplied to said receiving chamber against said spring, and relative to said valve to close said communication, a release valve in said receiving chamber having operating contact with said supply valve, a plunger having a seat for said release valve and cooperative therewith to control a communication between said receiving chamber and atmosphere and cooperative with said release valve upon closing such communication to move said supply valve relative to said one abutment, said plunger being subject to pressure of fluid in said receiving chamber and being movable thereby out of seating engagement with said release valve, a spring under pressure interposed between said plunger and release valve, and means for controlling movement of said plunger in the direction of any away from said release valve.

2. A self-lapping valve structure comprising in combination, two movable abutments cooperating to form a pressure chamber normally charged with fluid under pressure, a strut in said chamber having one end connected to one of said abutments, means connecting the opposite end of said strut to the other of said abutments, a coil spring in said chamber encircling said strut and bearing against said other diaphragm, a supply valve carried by said means and arranged to move axially of said other abutment for opening a communication between said chamber and a receiving chamber at the opposite side of said other abutment for supplying fluid under pressure to said receiving chamber for moving said abutments against said spring, a release valve having operating contact with said supply valve, a plunger movable axially of said valves and having a seat for said release valve and arranged to cooperate therewith for controlling communication between said receiving chamber and atmosphere, said plunger being movable into contact with said release valve for closing the communication controlled thereby and being then operable to move said release valve for moving said supply valve relative to said other abutment for opening communication controlled by said supply valve, a spring interposed between said plunger and release valve for biasing said plunger to a position for opening communication between said receiving chamber and atmosphere, another spring acting on said plunger biasing same to its communication opening position, and means for moving said plunger against the last named spring in the direction for closing said release valve and opening said supply valve.

3. A self-lapping valve structure comprising in combination, a movable abutment subject on one side to pressure of fluid in a chamber, a control spring acting on the opposite side of said abutment in opposition to pressure of fluid in said

chamber, a supply valve for supplying fluid under pressure to said chamber, a seat for said supply valve movable by and with said abutment in the direction of said supply valve upon an increase in pressure in said chamber, means acting on said supply valve urging same toward said seat, a release valve for releasing fluid under pressure from said chamber and having contact with said supply valve and operative to unseat same, a plunger subject to pressure of fluid in said chamber and having a seat for said release valve, said plunger being movable into contact with said release valve for closing the fluid releasing communication from said chamber and being then operative to actuate said release valve to open said supply valve, said plunger being also movable in the opposite direction, a spring interposed between said plunger and release valve operative to hold said release valve against movement upon movement of said plunger in said opposite direction for thereby opening the fluid releasing communication past said release valve, and means for controlling movement of said plunger.

4. A self-lapping valve structure comprising in combination a control spring, a movable abutment subject to opposing pressures of said spring and of fluid in a chamber, a supply valve, a release valve, said valves being of the poppet type coaxially aligned and movable in unison and arranged to seat in the same direction, seating means associated with said abutment having a seat for said supply valve, said supply valve being movable out of contact with said seat for supplying fluid under pressure to said chamber and said abutment being movable against said spring by pressure of fluid supplied to said chamber to move said seat into contact with said supply valve, a plunger coaxially aligned with said release valve and having a seat for engaging same, said plunger being operable upon seating engagement with said release valve to close a fluid release communication from said chamber and being then operative through said release valve to unseat said supply valve, said plunger being also movable in the opposite direction, a spring acting on said supply valve for urging same into contact with said seat, a spring interposed between said release valve and plunger for opening said release valve upon movement of said plunger in said opposite direction, and means for controlling movement of said plunger.

5. A self-lapping valve structure comprising a casing, a movable abutment in said casing having at one side a pressure chamber, a spring in said casing acting on the opposite side of said abutment, a sleeve in said casing arranged in coaxial relation with said abutment and having one end open to said chamber, a member in said chamber having sliding contact with said sleeve and secured to said abutment centrally thereof, a fluid pressure supply valve associated with said member and movable in the direction of said spring for supplying fluid under pressure to said chamber, pressure of fluid in said chamber being effective on said abutment for moving same against said spring for closing said supply valve, a spring acting on said supply valve for urging same to its closed position, a release valve engaging said supply valve, a plunger slidably mounted in said sleeve and having at one end a seat arranged to cooperate with said release valve upon movement of said plunger in the direction of said spring for closing communication between said chamber and a passage in said plunger leading to the atmosphere, said plunger being then op-

erative upon movement against said release valve to unseat said supply valve, and being movable in the opposite direction to provide for seating of said supply valve and movement away from said release valve, a spring interposed between said plunger and release valve operative to hold said release valve against movement upon seating of said supply valve, a bias spring acting on said plunger urging same in the direction away from said release valve, and means arranged to move said plunger in the direction of said release valve.

6. A self-lapping valve structure comprising a casing, a movable abutment in said casing having at one side a pressure chamber, a spring in said casing acting on the opposite side of said abutment, a sleeve in said casing arranged in coaxial relation with said abutment and having one end open to said chamber, a member in said chamber having sliding contact with said sleeve and secured to said abutment centrally thereof, a fluid pressure supply valve associated with said member and movable in the direction of said spring for supplying fluid under pressure to said chamber, pressure of fluid in said chamber being effective on said abutment for moving same against said spring for closing said supply valve, a spring acting on said supply valve for urging same to its closed position, a release valve engaging said sup-

ply valve, a plunger slidably mounted in said sleeve and having at one end a seat arranged to cooperate with said release valve upon movement of said plunger in the direction of said spring for closing communication between said chamber and a passage in said plunger leading to the atmosphere, said plunger being then operative upon movement against said release valve to unseat said supply valve, and being movable in the opposite direction to provide for seating of said supply valve and movement away from said release valve, a spring interposed between said plunger and release valve operative to hold said release valve against movement upon seating of said supply valve, a bias spring acting on said plunger urging same in the direction away from said release valve, means arranged to move said plunger in the direction of said release valve, another movable abutment arranged in coaxial relation with the first named abutment and being of the same area, the two abutments cooperating to form a chamber containing said control spring and normally supplied with fluid under pressure, and said supply valve being arranged to control supply of fluid under pressure from the last named chamber to said pressure chamber.

HARRY C. MAY.
